CONTINUOUS FILTER FOR CYANIDING AND THE LIKE.

APPLICATION FILED MAR. 28, 1907.

2 SHEETS—SHEET 2.

UNITED STATES PATENT OFFICE.

BERTRAM HUNT, OF SAN FRANCISCO, CALIFORNIA.

CONTINUOUS FILTER FOR CYANIDING AND THE LIKE.

No. 877,197.

Specification of Letters Patent.

Patented Jan. 21, 1908.

Application filed March 28, 1907. Serial No. 365,194.

To all whom it may concern:

Be it known that I, BERTRAM HUNT, a British subject, residing at San Francisco in the county of San Francisco and State of California, have invented new and useful Improvements in Continuous Filters for Cyanid- 5 ing and the Like, of which the following is a specification.

This invention relates to improvement in 10 continuous filters for cyanid and other purposes, the object of the invention being to provide a filter which will be rapid in its action, in which the filtering medium will always be maintained at its highest effi- 15 ciency, which will be automatic in its working, thus requiring little attention, which will require few repairs, and in which the power required for operating the movable parts shall be as small as possible.

20 In the accompanying drawings, Figure 1 is a vertical section of the apparatus; Fig. 2 is an enlarged section through the carriage; Fig. 3 is a broken plan view of the apparatus; Fig. 4 is an enlarged section through the 25 filter bed; Fig. 5 is an enlarged detail sectional view of a support for the filter.

Referring to the drawing, 1 indicates a 30 circular bed of concrete or like material, formed with exterior and interior circular 35 walls 2, 3, the surface of the end between said walls sloping downwardly outward, and the space between the walls forming a chamber for the filtered cyanid solution, the top of said chamber being formed by the filter bed, 35 of which the following is the construction. Upon said walls rest metallic rings 5, 6, having at the lower edges oppositely disposed flanges 7, 8, upon which are supported radial beams 10, upon which rest bars 11. Said 40 bars are triangular in cross section, and are arranged with apices upwards and with their bases in close proximity to, but not touching, each other, being spaced apart at a suitable distance, say, one-sixteenth of an inch. The 45 angular spaces between said bars are filled with clean sand, carefully screened, so as to consist of particles of approximately uniform size and of such fineness that it cannot pass through the spaces between the bottoms of 50 the bars, and this sand constitutes the filtering medium. The metallic rings 5, 6; extend above the top of the bars to a height commensurate with the amount of pulp to be fed to the filter. This pulp is fed by a 55 revolving carriage in the manner which I will now describe.

Resting centrally on the concrete bed is a tubular step 12, having an annular shoulder, 13, and upon said shoulder rotates a hollow hub 14 of a wheel 16. From said hub radiate 60 spokes 15, which extend slightly upward and are attached at the outer end to the rim of the wheel to which are secured brackets 17 in which are mounted the axles or rollers 20. Said rollers travel on the top of the outer 65 ring 6, which thus constitutes a circular track for said rollers. Secured on the outside of the wheel 16 is a channel-shaped sheave 21 by means of which the wheel can be driven by a rope from any suitable source of power. 70 Supported by two of the spokes of the wheel 16 is an inner beam, 22, and supported between the junctures of said spokes with the rim of said wheel is an outer beam 23 mounted in suitable bearings on the inner side of 75 said beams are axles 24 of wheels 25 which run on the inner and outer rings 5, 6. These beams and wheels constitute a carriage, which revolves over the filter bed and carries the ends of the pipes for discharging pulp 80 clean sand, and water, and also carries the means for removing the tailings.

The pulp which is to be filtered is supplied by a chute, 26, to a hopper, 27, the bottom of which rests within the top of a tube, 35, the lower end of which fits snugly within the upper end of the hollow hub 14, and has a circular flange, 31, resting upon the top of said hub. Said tube is divided into upper, intermediate and lower chambers, 28, 29, 30. 90 The upper chamber 28 is connected with the hopper and from the side thereof a pulp pipe 32 extends in a radial direction, the end of said pipe being bent at right angles and discharging on the rear side of a distributor 33. 95 Said distributor is supported from the carriage by means of hanger rods, 34, connected to the bottom 36 of the distributor, which slopes downward in two directions. The front or advancing portion forms the bottom 100 of the clean sand distributor box 37 while the rear portion forms the bottom of the pulp distributor box 38. The sides of said boxes are formed by the central wall 40, and the front and rear walls 41 and 42. The 105 pulp pipe discharges into the rear, or pulp distributor box, from which the pulp is distributed by means of small holes 43, in the bottom of the rear wall of said box, flowing down over the sloping extension of the bottom of said box, and being uniformly distributed over the filter bed. 110

The clean sand is supplied by a pipe 44 to an annular hopper 45, from which it is conveyed by a pipe 46 to the clean sand distributor box 37, from which it flows in the 5 same manner as the pulp, down the front sloping extension 47 of said box to the filter bed.

The intermediate chamber, 29, is connected with a clear water inlet pipe, 50, which 10 extends down through the bottom of the hopper, and from said chamber 29 lead radial pipes 51 extending over the filter bed and adapted to discharge clear water there-over. In order to remove the tailings after 15 the cyanid solution has been filtered therefrom, there is provided a sloping scraper 52 the lower edge of which travels in contact with the filter bed and which is supported by means of end blocks 53, suspended by hang- 20 ers, 54, from the beams 22, 23, and also by angular brackets, 55, extending rearwardly and upwardly and attached to said beams. The rear upper edge of said scraper is connected with the tubular casing 56 of a screw 25 conveyer 57, said casing being open opposite to said scraper. The shaft 60 of said conveyer is driven by a bevel gear 61, meshing with a bevel gear 62, on a vertical shaft 63, mounted in suitable bearings on the tube 35, 30 said shaft carrying a gear wheel, 64, which meshes with a gear wheel 66, carried by a rope sheave 67, by means of which power may be applied from any distant source. In this manner the tailings are conveyed to the 35 chamber, from which they drop through the tubular step 12 into a chamber 68 from which they are conveyed to the outside of the bed by means of a screw conveyer, 69.

The clear liquid which is drawn through 40 the filter falls into compartments 70, which are separated by radial walls 71, and connected by valves 72, with a circular main pipe 73, outside the concrete bed. After the scraper has passed over the filter bed and removed from the top of said bed the fine residues of the pulp or slimes, the part of the filter bed between the edge of the scraper and the distributor then consists of clean sand only, through which air can pass very 45 readily, and the result is that, owing to the porous quality of this clean sand and the ready passage of air therethrough, the vacuum which is furnished to draw the solution through the filter is greatly impaired. It is 50 for the purpose of avoiding the reduction of the vacuum which would thus be occasioned, that the receptacle for the solution is divided into compartments, and each compartment in turn, as the part of the carriage between the 55 edge of the scraper and the distributor passes thereover, is cut off from the main pipe 73. This is done by means of arms, 74, 75, secured to the carriage, which arms operate upon the valves controlling the compartments 60 the front arm 74 turning the valve to

close the same and the rear arm 75 turning it to re-open it. In consequence, said valve is closed while the porous portion of the filter bed is passing immediately thereover.

The apparatus is intended particularly for the treatment of what is known as slimed or very finely crushed material, which may be here designated as pulp.

Before arriving at the machine, the pulp is preferably treated by a hydraulic classifier to separate out a portion of the sandy part of the pulp. The sandy portion is carried by the pipe 44 into the sand distributor box and is then distributed over the filter bed immediately behind the scraper. The slimy, or clayey portion, is fed into the hopper by the chute 26, and is carried by the pulp pipe 32 and is fed into the pulp distributor box; thence it is distributed over the filter bed behind the clean sand. A 85 vacuum is produced in the main pipe 73, which draws liquid and air through the filter bed into the several compartments of the receptacle therefor. As the carriage rotates, the scraper takes the tailings or residue off, 90 and these tailings are carried into the conveyer and discharged. Wash water may be discharged by the radial pipes 51 upon the filter bed at any desired distance behind the carriage to wash the pulp after the solution 95 has been drawn off.

I claim:

1. A filter comprising a stationary filter bed, a feeder movable over said bed for distributing thereover the material to be filtered, a scraper also movable over said bed for removing the residual material, and means for moving said feeder and scraper over said bed, substantially as described.

2. A filter comprising a stationary annular filter bed, a feeder for feeding on to said bed the material to be filtered, a scraper for scraping the residual material from said bed, and means for revolving said feeder and scraper over the bed, substantially as de- 105 scribed.

3. A filter, comprising an annular filter bed, a carriage revolving thereover and means supported by said carriage for discharging on said bed the material to be filtered, and for removing from the filter bed the residual material thus filtered, substan- 110 tially as described.

4. A filter, comprising a stationary annular filter bed, a carriage revolving over 120 said bed, a feeder for feeding on to said bed the material to be filtered, scraper for removing from said bed the residual material, a conveyer to which the material is delivered by the scraper and adapted to convey the 125 material from the bed, said feeder, scraper and conveyer being movable with the carriage, and means for automatically operating said conveyer with the movement of the carriage, substantially as described.

5. A filter comprising a stationary annular filter bed, a carriage revolving over said bed, a feeder for feeding on to said bed the material to be filtered, clean sand distributor arranged to distribute clean sand over the filter bed in the rear of the scraper, a scraper for removing from said bed the residual material, a conveyer to which the material is delivered by the scraper and adapted to convey the material from the bed, said feeder, distributor, scraper and conveyer being movable with the carriage, and means for automatically operating said conveyer with the movement of the carriage, substantially as described.

6. A filter comprising a suitable base having inner and outer circular walls to form therebetween an annular receptacle for the clear liquid, a stationary annular filter bed on said walls, a carriage adapted to travel on said walls, a pulp distributor and a scraper supported by said carriage, means for conducting pulp from a central point relative to the bed to said carriage, and means for

conducting the residual material from the 25 scraper to such central point, substantially as described.

7. A filter comprising a suitable base having inner and outer circular walls to form therebetween an annular receptacle for the 30 clear liquid, a stationary annular filter bed on said walls, a carriage adapted to travel on said walls, a pulp distributor, a clean sand distributor and a scraper supported by said carriage, means for conducting pulp and 35 clean sand from a central point relative to the bed to said carriage, and means for conducting the residual material from the scraper to such central point, substantially as described.

In testimony whereof I have hereunto set my hand in the presence of two subscribing witnesses.

BERTRAM HUNT,

Witnesses:

FRANCIS M. WRIGHT,
D. B. RICHARDS
